UNITED STATES PATENT OFFICE.

SPENCER B. PEUGH, OF SALEM, INDIANA.

IMPROVEMENT IN SHINGLE-MACHINES.

Specification forming part of Letters Patent No. **150,480**, dated May 5, 1874; application filed February 28, 1874.

To all whom it may concern:

Be it known that I, SPENCER B. PEUGH, of Salem, in the county of Washington and State of Indiana, have invented a new Improvement in Shingle-Machines for sawing shingles, of which the following is a specification:

In the accompanying drawing, Figure 1 represents a top view of my attachment to saw-mill carriage for sawing shingles; Fig. 2, a vertical transverse section of the same on the line *c c*, Fig. 1; and Fig. 3, a detail side view of block, showing manner of cutting the shingles, with alternating butts and points.

Similar letters of reference indicate corresponding parts.

The invention will first be fully described, and then pointed out in the claim.

A in the drawing represents a carriage of the usual construction, for moving the log against the circular saw. To the outermost lateral head-blocks B of the carriage are hinged lever-rods C, which turn on pivot-pins *a*, placed nearly level with the top of blocks B. Rods C extend sidewise along the head-blocks, and connect at the rear ends, by pivoted links *b*, with a longitudinal crank-rod, *d*, which is supported in staples or hinges *e* of the side piece of the carriage, and turned by means of a hand-lever, *f*, at one or both sides. Links *b* are pivoted to the arms of the crank-rod *d* at such a distance from the same that the lever-rods C may be thrown alternately into inclined position, as required, to feed the shingle-blocks to the saw for obtaining the tapering shape of the shingles. The position of lever *f* is changed after the carriage has passed the saw, and retained during the time of passage by means of suitable rack or ratchet arrangement. The block-fastening frame D is guided, by rails *g*, along the lever-rods C, and moved toward and from the saw in the same manner as the logs. The extent of motion of frame D is defined by bottom stops *h*, which come in contact with the pivot-pins *a* of the carriage, and rear stops *h'* of head-blocks B.

Frame D is constructed of longitudinal pieces D', which are recessed at the side, facing the saw, for the shingle-blocks E. Any number of blocks E may be arranged on the carriage, according to the size of the same. The base-piece D' is provided under the recesses with stationary projecting jaws F, which take hold of the blocks from below, while the pivoted top jaws F' are swung on the top of the blocks, and firmly driven into the same. The top jaw F' is of U shape, as shown in Fig. 1, and has sharp teeth or spurs *i*, which enter into the block, and hold the same firmly in connection with the teeth of the lower jaws F.

The shingle-blocks are cut from the log in the size of the shingles required, firmly attached to the block-fastening frame D, and fed, by the motion of the carriage, to the saw. Each trip of the carriage cuts off a shingle from each block. The inclination of the block is then changed for the next trip by lever *f*, so that shingles with alternating butt and point ends are cut from the blocks. The regular size of the shingles is then produced from the sections so cut by ripping them to proper width by a smaller saw.

The blocks are cut off into shingles as fast as a log can be cut into planks, so that shingles are thus produced, by a simple arrangement, out of the whole blocks without any splitting.

The block-fastening frame may be easily taken off when not required, and the carriage then used for the ordinary purposes.

Having thus described my invention, I claim as new and desire to secure by Letters Patent—

The detachable shingle-block-fastening frame D, constructed of recessed pieces D' with projecting stationary bottom jaws F, and pivoted top jaws F', substantially as set forth.

SPENCER B. PEUGH.
